ANSWER

Earl Elwin Berry

By Patricia Miller Attys.

UNITED STATES PATENT OFFICE.

EARL ELWIN BERRY, OF BELOIT, WISCONSIN, ASSIGNOR TO BELOIT IRON WORKS, OF BELOIT, WISCONSIN.

PAPER-UNWINDING STAND WITH WATER-COOLED DRUM.

Application filed April 18, 1924. Serial No. 707,403.

In paper making machines, after the paper leaves the calenders at the dry end of the machine, it must be gotten into a form that can be readily handled. To accomplish this result, it is generally necessary to trim the edges and slit the sheet into several strips; and the first step in this process is to wind the paper on a reel after leaving the calenders. The roll of paper is taken and placed in an unwinding or reeling-off stand, preparatory to being run through slitters and onto a rewinder positioned adjacent the reeling-off stand.

Heretofore a great deal of trouble has been experienced with reeling-off stands on account of the excessive friction which has a tendency to burn up the brake friction bands, thereby causing delays and repair expenses. Reeling-off stands have also been provided with means for cooling off the brake mechanisms but such stands have all been of the back gear type making a very expensive reeling-off unit wherein the gear members are subject to very rapid wear and to gear breakage.

This invention relates to a reeling-off stand for a paper making machine, said stand being provided with a water-cooled brake drum and furthermore being of a gearless type wherein a reel of paper may be quickly and simply inserted in place and connected with the drum by an improved shiftable driving coupler or connector.

It is an object of this invention to provide a gearless type of a water-cooled unwinding stand for a paper making machine.

It is also an object of the invention to provide a reeling-off stand wherein a shiftable coupler engaged in the drum journal is adapted to be readily connected with a reel of paper which is mounted on the stand for rewinding.

It is a further object of this invention to provide a reeling-off stand wherein the reel of paper may be adjusted on the stand together with the coupler without requiring movement of the brake drum or uncoupling of the friction bands.

It is furthermore an object of the invention to provide a paper making machine with an unwinding or reeling-off stand wherein the reel of paper to be rewound may be set at different angles with respect to the commercial rewinding machine.

It is an important object of this invention

to provide a paper making machine with a reeling-off stand, the controls for which are all placed on the front side of the machine within easy reach of an operator, said reeling-off stand having a coupler which is shiftable within the brake drum journal and has pins adapted to be removably engaged in a notched end of the spool shaft.

Other and further important objects of this invention will be apparent from the disclosures in the specification and accompanying drawings.

The invention (in a preferred form) is illustrated on the drawings and hereinafter more fully described.

On the drawings:

Figure 1 is a front end elevation of a reeling-off stand embodying the principles of this invention and positioned adjacent one end of a rewinding machine, a fragmentary end portion only of which is illustrated.

Figure 2 is a fragmentary side elevation of the reeling-off stand.

Figure 3 is an enlarged fragmentary detail section taken on line 3—3 of Figure 1 with parts in elevation.

Figure 4 is a fragmentary detail view taken on line 4—4 of Figure 3 with the reel shaft omitted.

Figure 5 is a detail view taken on line 5—5 of Figure 2 with the coupler omitted.

Figure 6 is an end elevation of the reeling-off stand taken on line 6—6 of Figure 2.

As shown on the drawings:

The reference numeral 1, Figure 1, indicates a rewinding machine provided with trimming and slitting mechanisms 2 adapted to trim the edges and slit the sheet of paper before rewinding of the same on commercial reels. The slitting and rewinding units form a part of a paper making machine and are located beyond the dryer end of a Fourdrinier. At the dryer end of the Fourdrinier unit, the paper which has been made and after leaving the calender, is wound on a spool or reel.

Positioned between the dryer end of the Fourdrinier (not shown) and the rewinding unit 1 is a reeling-off stand embodying the principles of this invention. The reeling-off stand comprises a pair of pedestals or brackets 3 and 4 having mounted on the tops thereof bearing frames 5 and 6 respectively. Supported in the bearing frames 5 and 6 are bearing blocks 7 having eyebolts 8 there-

on for engagement by lifting chains to permit removal of a spool or reel from the pedestals 3 and 4. A spool or reel cylinder 9 having a roll of paper 10 thereon is removed 5 from the calender winding machine and after having the bearing blocks 7 engaged on the journals 11 thereof, the reel cylinder with the roll of paper thereon is transferred onto the pedestals 3 and 4 with the bearing blocks 7 10 engaged in the bearing frames 5 and 6.

The bearing frame 5 is slidably mounted on the top of the pedestal 3 longitudinally of the axis of the bearing and is adapted to be adjusted thereon by means of an adjusting 15 screw 13 operable by a vise handle 14. The bearing frame 6 is slidably mounted on top of the pedestal 4 at right angles to the axis of the reel cylinder and is adapted to be operated by a bell-crank 15 supported on a 20 block 16 slidable in a vertical slot 17 in the pedestal 4. The lower end of the bell-crank 15 is pivoted through an elongated slot 56 to a crank arm 18 mounted on one end of a shaft 19 journalled in bearings on the lower 25 portions of the pedestals 3 and 4. A crank arm 20 is mounted on the opposite end of the shaft 19 and has an adjusting screw 21 connected therewith operable by means of a hand wheel 22.

30 Formed on one end of the reel cylinder shaft or journal 11 to the outside of the bearing frame 5 is a coupler 23 having a pair of radial notches 24 which communicate with arc-shaped slots 25. A connecting bar or rod 26 is provided having coupling pins 27 radially mounted near one end thereof adapted to be projected through the coupler notches 24 and seated in the slots 25. The connecting rod 26 has a squared head 28 integrally 35 formed on one end thereof and is slidably disposed within a squared recess 29 formed within a journal 30 integral with a brake drum 31. The inner end of the brake drum journal 30 is closed as illustrated in Figure 3. 40 Integrally formed on the opposite end of the brake drum 31 is a journal 32 open at both ends. The journal 32 is supported within a bearing 33 mounted upon the top of a stand or pedestal 34. Rigidly supported on the 45 pedestals 3 and 34 is a frame section 35 having a bearing 36 mounted on the top thereof for supporting the brake drum journal 30. Secured to the outer end of the brake drum 31 is a hand wheel 37 for the purpose of turning the drum and the connector 26 to permit the coupling pins 27 to be removed from the 50 coupling slots 25 through the notches 24.

Engaged around the brake drum 31 is a 55 lined brake band 38, one end of which is connected to one arm of a bell-crank 39. The other end of the brake band 38 is connected to a bolt 40 pivoted on the other arm of the bell-crank 39. The bell-crank 39 is secured on one end of a shaft 41 journalled in a bearing sleeve 42 formed on the frame section 35.

Connected to the other end of the shaft 41 is a lever or bar 43, the lower end of which is connected to be operated by a connecting rod 44. The connecting rod 44 extends from the reeling-off stand to the rewinding unit 1 and is connected to one arm of a bell-crank 45 pivoted on the frame of the rewinding unit. The bell-crank 45 has the other arm thereof connected to a control screw 46 which is operable by means of a hand wheel 47 engaged 75 on the upper end thereof.

Supported by means of a bracket 48 on the pedestal 34 is a water discharge housing or globe 49 into which the drum journal 32 projects. Projecting into the outer end of a 80 sleeve 50 formed on the housing 49 is an elbow 51 to which a water supply pipe 52 is attached. Connected in the inner end of the housing sleeve 50 is one end of a water pipe 53 which projects through the drum journal 32 into the interior of the drum to supply 85 cooling water thereto. A water discharge or return pipe 54 is connected in an outlet sleeve 55 formed on the bottom of the housing 90 49.

The operation is as follows:

From the breast roll to the calenders, the manufacture of paper is a continuous process, and after leaving the calenders, the paper is wound upon a reel or spool from which it is removed and rewound in a form that can be readily handled. A roll of paper from the calender is transferred with the spool 9 to the reeling-off stand with the spool journals 11 engaged in the bearing blocks 7 on the pedestals 3 and 4. The brake drum 31 is now manually turned by means of the hand wheel 37 until the coupler pins register with the coupler notches 24. The connecting rod 26 is then pulled out from the drum journal 30 and projected into the end of the coupler 23 to permit the coupler pins 27 to be engaged in the coupler slots 25 as illustrated in Figure 3. The spool 9 with the roll of paper 10 thereon is thus easily and quickly connected with the brake mechanism through the flexible joint afforded by the coupler 23 and the slidable connecting rod 26 which carries the coupler pins 27.

The reeling-off stand holds the roll of paper 115 as it comes from the paper making machine and is adapted to give the paper the proper tension when it is being rewound in commercial size rolls on the rewinder unit 1. The brake mechanism is used to control the paper tension and the brake band 38 is subjected to severe service and the speed of the drum acting within the brake band will soon heat up the brake mechanism. To cool the brake drum, water from the pipe 52 passes through the pipe 53 into the drum 31 and serves to cool the same. The water is permitted to pass out of the drum journal 32 into the housing 49 and is discharged through the outlet pipe 54.

Since the paper from the paper machine does not always wind up the same, it is sometimes necessary to offset or adjust the spool 9 longitudinally. This is done by means of the vise handle 14 and the screw 13 causing the connector 26 to slide in the drum journal 30 without necessitating any longitudinal movement of the brake drum or ever requiring uncoupling of the brake band.

10 It sometimes becomes necessary to set the spool 9 at different angles with respect to the rewinding unit. This is done by operating the hand wheel 22 which actuates the shaft 19 and the bell-crank 15, whereby the bearing 15 frame 6 may be set as desired.

10 The brake band 38 is adjusted by means of the bell-crank 39 and the lever 43 through the shaft 44 and bell-crank 45. The bell-crank 45 is actuated by the screw 46 operable by 20 means of the hand wheel 47.

15 The paper from the roll 10 (Figure 1) is conducted from the reeling-off stand to the rewinding unit 1 where the paper is first run through the slitters and trimmers 2 and is 25 then rewound in commercial sizes.

Attention is directed to the simple arrangement whereby the spool or reel 9 on the reeling-off stand may be quickly and easily connected with the brake mechanism by means 30 of the slidable connector 26, one end of which has the squared head 28 movable in the drum journal 30, while the other end of said connector carries the coupler pins 27 for engagement with the notched and slotted end of the 35 coupler 23 formed on one of the spool journals 11. With the improved coupler mechanism for the reeling-off stand, a paper roll spool may be engaged in place on the stand pedestals or removed therefrom without requiring 40 any uncoupling of the brake band or the like. Breakage and wear of back gearing is entirely done away with making a reeling-off stand of materially less cost and much simpler in construction and operation. The various controls for adjusting the spool on the pedestals 45 are all conveniently located at or near the front side of the machine.

I am aware that numerous details of construction may be varied through a wide range 50 without departing from the principles of this invention, and I therefore do not purpose limiting the patent granted, otherwise than necessitated by the prior art.

I claim as my invention:

55 1. In a reeling-off stand the combination with a spool and a brake mechanism, a journal formed on said brake mechanism and closed at its inner end, a coupler formed on

the spool and having communicating notches and slots therein, a connecting bar, a squared 60 head on one end thereof slideable in a squared recess in said journal, pins on the other end of said connecting bar, and a hand wheel on the brake mechanism for turning the same and said connecting bar to position the pins 65 for engagement in the coupler slots.

2. In a reeling off stand, supporting members, a spool rotatably supported by said members, a brake mechanism, and a unitary separable connecting bar adapted to be slidably engaged with said brake mechanism and 70 removably engaged with said spool, the ends of said bar being supported by said brake mechanism and said spool respectively.

3. In a reeling off stand, supporting members, bearing frames supported thereby, one of said bearing frames being adjustable longitudinally of said stand and the other of said bearing frames being adjustable at right angles thereto, a spool, and bearing blocks 80 adapted to receive the journals of said spool and to be movable therewith as a unit, said bearing blocks being supported normally in said bearing frames.

4. In a reeling off stand, supporting members, bearing frames supported thereby, a spool, bearing blocks for receiving the journals of said spool adapted to be received by said bearing frames, means for adjusting one of said frames longitudinally of the axis of 90 said spool, and means for adjusting the other of said frames at right angles thereto.

5. In a reeling off stand, supporting members, bearing frames supported thereby, a spool, bearing blocks for receiving the journals of said spool adapted to be received by said bearing frames, means for adjusting one of said frames longitudinally of the axis of 95 said spool, and means for adjusting the other of said frames at right angles thereto, said 100 means having controls positioned on the front side of the stand within easy reach of an operator.

6. In a device of the class described, a brake mechanism comprising a hollow drum 105 having a hollow trunnion formed on one end for admitting a cooling fluid, the other end being provided with a rectangular shaped recess, a spool separately supported, and a connecting bar having a squared end adapted to 110 be slidably held in said recess, the other end of said bar being adapted to be removably coupled with said spool.

In testimony whereof I have hereunto subscribed my name.

EARL ELWIN BERRY.
